UNITED STATES PATENT OFFICE.

CHARLES VISTARD, OF ALBERT, WEST VIRGINIA.

DESIGN FOR A MINER'S LAMP.

44,079.

Specification for Design.

Patented May 20, 1913.

Application filed February 28, 1913. Serial No. 751,366. Term of patent 3½ years.

To all whom it may concern:

Be it known that I, CHARLES VISTARD, a citizen of the United States, residing at Albert, in the county of Tucker, State of West Virginia, have invented a new, original, and ornamental Design for Miners' Lamps, of which the following is a specification, reference being had to the accompanying drawing, forming a part thereof, in which—

Figure 1 is a front elevation. Fig. 2 is a

side elevation, and Fig. 3 is a top plan view of a miner's lamp embodying my design.

I claim:—

The ornamental design for a miner's lamp, as shown.

CHARLES ^{his} VISTARD.
